(57) **CLAIM**

The ornamental design for a model vehicle battery charger as shown and described.

DESCRIPTION

FIG. 1 is an upper, left, front perspective view of a model vehicle battery charger showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is an upper plan view thereof;

FIG. 8 is a lower plan view thereof;

FIG. 9 is a right side elevation view thereof; and,

FIG. 10 is a left side elevation view of the model vehicle battery charger.

In the drawings, the broken lines illustrate portions of the model vehicle battery charger that form no part of the claimed design.
